GROUP SELECTOR FOR SORTING MACHINES

Ernest Rose, Washington, D. C., assignor to International Business Machines Corporation, New York, N. Y., a corporation of New York

Application December 20, 1934, Serial No. 758,531

23 Claims. (Cl. 209—110)

This invention relates to a group selector for sorting machines, particularly of the well known Hollerith type, whereby documents of several classifications may be sorted by setting a single control member.

It is an object of the invention to provide means for accomplishing the sorting or selection of a group of cards or documents having indicia thereon adjacent to a desired indicia so as to take care 10 of any errors in originally determining the value of the indicia upon the cards or documents. The invention aims to counteract and eliminate the errors due to the human factor in compiling the data subsequently transposed or punched 15 upon the cards or documents.

It is a further object of the invention to provide a single instrumentality which may be set by one motion for the actual setting of the selecting means whereby errors in the actual setting 20 of the sorting machine are also eliminated and making the actual setting simple and foolproof.

On machines at present in use it is necessary to set a plurality of means in order to accomplish a sorting of several classifications. By providing 25 in accordance with the present invention a unitary means, the setting of the sorting machine for sorting any group of contacts can be accomplished more quickly and surely and thereby the time required for classifying, searching and 30 paring master prints on file may be considerably shortened.

The invention is designed particularly for the sorting of finger print records but can be adapted for records of various types where the same factors are present.

It is a further object to provide means whereby the number of classifications selected are increased with the higher value of the data upon the documents whereby the greater possibility of 40 error is compensated by a wider selection.

The invention is designed to provide a selecting arrangement which can be used with a sorting machine with a minimum of alterations therein.

Various other objects and advantages of the 45 present invention will become apparent from the detailed description below and will be particularly pointed out in the following description and claims and shown in the preferred embodiment of the invention illustrated in the drawings, in 50 which

Figure 1 is a diagrammatic view of a sorting machine and shows the card feeding and conveying mechanism, the card guiding devices and the analyzing device.

55 Figure 2 is a vertical elevation of the brush

holder and special analyzing brush shown in Figure 1 and viewed from the left in the latter figure.

Figure 3 is a detail view in elevation showing the driving connections between the selector device and the sorting machine.

Figure 4 is a perspective view of a battery of control blocks with various details and the selector slides omitted for greater clearness illustrating the manner in which they are assembled.

Figure 5 is a perspective view of a battery of 10 stationary commutators to cooperate with the control blocks shown in Figure 4 with certain details omitted for clarity and illustrating the manner in which said commutators may be assembled.

15 Figure 6 is a side elevational view of a single control block.

Figure 14 is a side view of a stationary commutator which cooperates with a selector block,

Figure 15 is a partial cross sectional view 40 through the battery of stationary commutators, and

Figure 16 is a circuit diagram with certain of the commutator-control block circuits omitted for greater clarity showing the manner in which 45 the invention is connected to the sorting machine.

The present invention has been shown as applied to a sorting machine of a type now well known in the art. The construction and operation of the card selecting, conveying and guiding mechanism and the general arrangement of the circuits are fully shown and described in Letters Patent No. 1,741,985, granted December 31, 1929 to E. A. Ford, while the mechanism for feeding cards from the magazine and the brush 50

holder for the analyzing brush are shown and described in Letters Patent No. 1,741,992, granted December 31, 1929 to Harry Kleckler.

The foregoing mechanisms will be only briefly explained herein since said patents contain a full description of well known mechanisms of which the present invention is an improvement.

The motor 10 which drives the sorting mechanism is started by depressing a starting key 11 which establishes a circuit from source 12, line 13, motor relays 14, card relay 15, starting key 11, now closed, stop key 16, to the line 17 and back to source 12. Energization of relays 14 closes contacts 14a thereby starting the motor 10 while energization of relay 15 closes contacts 15a and connects the card lever contacts 18 in parallel with the starting key 11. The starting key 11 is held depressed until cards begin to pass the analyzing brushes after which the card lever contacts 18 close thereby establishing a holding circuit for the relays 14 and 15. The starting key 11 may be released after the contacts 18 have established the holding circuit. When the last card has been fed from the card magazine and has passed the analyzing brush the card lever contacts 18 open thereby breaking the holding circuit for relays 14 and 15 and the motor stops. The motor may also be stopped at any time by depressing the stop key 16 which opens the holding circuit in a similar manner.

The motor 10 is connected by suitable driving connections such as a belt or gearing to a main drive shaft 19 (Fig. 1) and drives the feeding rollers 20 by means of suitable gears 21 and 22. The cards 23 are fed from the magazine by means of a picker 24 carried by a reciprocating frame 25 sliding in suitable guides and operated by eccentric pins 26 carried by a cross shaft (not shown) driven by the shaft 19. A link 27 connects each pin 26 to a rock arm 28 journaled upon a cross shaft 29, each of the arms 28 having a slot at its upper end which engages a pivoted member carried by the frame 25. It will be clear therefore, that rotation of shaft 19 will cause the frame 25 to reciprocate from right to left (Fig. 1) to feed a card 23 from the magazine. The timing of the parts is such that a card 23 is fed from the magazine once during each revolution of the feed rollers 20. Extending crosswise of the machine above and parallel with the shafts supporting the card feeding rollers 20 is a bar 30 adapted to support and guide a carriage 31 carrying a detachable brush holder 32. The carriage 31 is adapted to be shifted manually and crosswise of the machine or front and rear, as viewed in Fig. 1, and carries a post 33 which cooperates with a hole 34 in the brush holder 32 to hold the latter in place. The brush holder 32 is locked in place by means of a rotatable pin 35 having a notch 36 near its mid-point of about the same radius as the pin 33 while the latter has a similar notch 37 near its end of a radius about equal to the radius of the pin 35. When both notches 36, 37 are facing each other the brush holder 32 may be easily removed but if a handle 38 carried by pin 35 is turned about 90° the notch 36 in pin 35 is rotated to the position shown in Fig. 1 and the solid part of the pin 35 will be brought into the notch 37 in pin 33 and thereby prevents removal of the brush holder 32.

Ordinary sorting operations of the sorting machine require a single brush which may be of the form disclosed in Patent 1,741,992 in which the brush holder is composed of two parts which

are insulated from each other, the lower part being of metal permanently fastened to the upper part and carries a card analyzing brush and a contact shoe. The contact shoe bears upon a contact rail 39 carried by the bar 30 and insulated therefrom so that the brush may be set to analyze any desired column of the card and still remain connected to the control circuits of the machine.

When it is desired to carry out the special sorting operation whereby several classifications may be sorted, the ordinary brush holder is removed and replaced by a special brush holder having twenty brushes adapted to analyze simultaneously twenty adjacent columns of the record card.

The special brush holder is illustrated in Figs. 1 and 2 in which it is shown as comprising a substantially U-shaped frame 32, between the downwardly extending arms 40 of which are supported twenty brush retainers 41 insulated from each other and from the frame 32. The brush retainers 41 carry the brushes 42 which are held in place by set screws 43 the lower ends of the retainers being slotted, as at 44, to permit the brushes to flex under the pressure they exert upon the card as it passes over the rotatable and insulated contact roll 45.

The brush retainers 41 are supported by pins 46 which pass through the arms 40 of holder 32 and are held in said arms by means of pins 47 which pass through the arms 40 and the pins 46, suitable insulating bushings surrounding the pins 46 and preventing the metal of the brush retainers from touching the pins 46. The retainers 41 are insulated from each other and from the arms 40 by means of flat separators 48 of insulating material and each is provided with a connector lug 49 to which are soldered or welded the individual wires 50 connecting the brushes 42 to the selector circuits. Interposed between the extreme right and left separators 48 (Fig. 2) and the arms 40 are plates 51 cooperating with set screws 52 carried by the arms 40. It will be clear that the set screws 52 may be turned in either direction to adjust the brushes slightly in a direction axial with respect to the set screws 52 and, when said brushes have been once set properly, said screws 52 may be both tightened to hold the brush retainers firmly in place. The individual wires 50 may be cabled and of a sufficient length to permit setting the carriage 31 to position the brushes in coincidence with any twenty columns of the record card as it passes over the contact roll.

Before proceeding with a detailed description of the special selector mechanism a brief description will be given of the operation of the sorting machine when operated in the ordinary manner. The single brush used for normal sorting operations is indicated by broken lines (Fig. 16) and bears the reference numeral 53. It will be understood that the special brush holder 32 has been replaced by the ordinary brush holder having a single brush and that the special selector circuits, hereinafter to be more fully described, have been disconnected by means of certain switches provided for that purpose. The brush 53 is positioned to analyze the desired column on the record card as the card is fed from the first set of feed rollers 20 (the right set, Fig. 1). The guide blades 54 rest upon the top of an armature 55 which is controlled by a sorting magnet 56, the armature lying level with and between two fixed guide plates (not shown) over which the card is adapted to slide under the influence of 75

the feed rollers 20. The ends of the guide blades 54 are so spaced relative to the analyzing brush that the brush will sense an index-point perforation at the instant the left edge of the card 5 underlies the end of the guide blade 54 corresponding to that index point position. Each guide blade leads to a sorting pocket (not shown) which is designed to accumulate all of the record cards having a given index-point perforation in 10 the column analyzed.

There are thirteen such sorting pockets, the thirteenth pocket being for the reception of unperforated cards and commonly called the "reject" or "R" pocket. The other twelve pockets 15 correspond to the twelve index-point positions of the record card and each has a guide blade 54 leading thereto. The first blade on the right (Fig. 1) corresponds to the "9" pocket, the next corresponds to the "8" pocket, and the others in 20 order, from right to left, correspond to the "7", "6", "5", "4", "3", "2", "1", "0", "11", and "12" pockets, respectively.

As the card passes beneath the brush 53, the left edge passes beneath each blade end and, 25 if a perforation should be present in any of the index point positions named, said perforation will be sensed by the brush 53 at the same instant the left edge of the card underlies the end of the particular blade 54 corresponding to the sorting 30 pocket adapted to accumulate cards perforated at that particular index-point.

When the perforation is sensed by the brush 53 contact will be made with the contact roll 45 and a circuit established as follows: Source 12, line 35 13, sorting magnet 56, brush relay 57, line 58, contact rail 39, brush 53, contact roll 45, contact roll brush 59, commutator brush 60, through the commutator segment corresponding to the index-point perforation sensed, common brush 61, line 40 17, back to source 12. Energization of the brush relay 57 closes contacts 57a and establishes a holding circuit for the relay 57 through a commutator segment 62, brush 63 and the common brush 61 to the source 12. The segment 62 is of 45 sufficient circumferential length to hold the circuit until the last index-point position has passed beneath the brush, after which event occurs, the brush 63 passes out of contact with said segment 62, thereby breaking the holding circuit for relay 57. The energization of the sorting magnet 56 50 causes the armature 55 to drop thereby lowering all of the blade ends 54 not resting upon the record card analyzed and, as a consequence thereof, a gap is made between the last blade on the left (Fig. 1) which is held up by the card and the next adjacent lowered blade into which the card is carried by the feeding rollers 20. The card will thereafter be guided to the appropriate sorting pocket by means of suitable feeding rollers similar to the rollers 20.

Patent No. 1,741,985 gives a more detailed description of the construction and operation of the commutator 64 cooperating with the brushes 60, 61 and a reference to that patent will fully explain its purpose. Since the present invention 65 does not directly involve the said commutator it will not be described in detail herein. It will be understood that each bar or spot 65 on the commutator has been made current conducting in each index point position as explained in detail in said patent.

The special group selector device is arranged to be attached to an existing sorting machine without any structural alteration in the machine 70 and for that reason may be made a compact and

self-contained unit or may be preferably divided into two units as shown in Fig. 1 in dotted lines at 66 and 66A. The casing 66 containing the battery of stationary commutators hereinafter described may be attached to the rear of the 5 machine and near the right end of the machine and is shown particularly in Figs. 5, 13, 14, and 15. The casing 66A containing the battery of selector blocks and preferably flexibly electrically connected with the casing 66 is preferably positioned 10 at the front of the sorting machine so as to permit easy access thereto.

Journalled within the casing 66 is a shaft 67 which extends forwardly and exteriorly of the casing (to the left Fig. 3) and carries mounted 15 thereon a gear 68 meshing with the gear 22 carried by shaft 19 and driving the lower right feed- 20 ing roller 20 (Fig. 1). The gear 68 has a hub which extends through an outboard bearing 69 carried by a bracket 70 attached to the left side 20 of the casing 66.

The shaft 67 has mounted thereon a series of brush holders 71, twenty in number, and a brush holder 72 cooperating with the commutator block 73 which shunts the sorting magnet 56. The 25 brush holders 71 and 72 are insulated from the shaft 67 in any desired manner such as by the insulating rings 74.

Located within the casing 66 are preferably four supporting rods 75 for the commutator 30 blocks 76 and the above mentioned block 73. The blocks 76 and the block 73 are made of insulating material such as bakelite or the like and are spaced from one another by the spacers 77 carried by the rods 75 thereby providing spaces 35 through which the leads to the contacts 78 upon the blocks 76 and to the contact 79 upon the block 73 may be led.

As mentioned above, the brush holders 71 and the brush holder 72 are insulated from the shaft 40 67 by the rings 74. These insulating rings are fixedly secured to the shaft 67 in any desired manner and the brush holders 71 and 72 are in turn fixedly secured to the insulating rings 74 by means of the set screws 80. This permits any 45 circumferential and axial adjustment desired for the brush holders upon shaft 67. The brush holders are made of conducting material such as copper or the like and are provided with an annular groove 81 against which bears a flexible 50 lead 82 secured to a side of the blocks 76 and 73 as for example by the screws 83.

Secured adjustably in the holders 71 by means of the set screws 84 are the brushes 71' and secured in holder 72 in like manner is brush 72'. 55

The stationary commutators have the contacts 78 therein which constitute the commutator bars and are insulated from each other. There are twelve commutator bars numbered as shown in Fig. 14 from 0 to 9 and 11 and 12. As above 60 mentioned, twenty commutator blocks 76 are provided although a greater or less number may be provided depending upon the special type of work or rather cards which are to be sorted. The present illustrated form of the invention is primarily 65 designed for finger print card sorting in which there are usually twenty-six tabulated positions upon the record card besides the "all out" position. In order to take care of these positions two commutators 76 are associated together and 70 therefore a bank of twenty is provided which will analyze all ten fingers at once. The code used whereby this is done will be described in detail below.

The brush 71' contacts the fixed commutator 75

bars in succession and each brush 71' is connected in series with the brushes 42 previously described. As previously mentioned there are twenty brushes 42, but in Fig. 16 the connections to the first and second commutators are only shown although it is to be understood that the remaining brushes and commutators are similarly connected.

It is to be noted that each circumferential row of commutator bars in each block 76 corresponds to a column on the record card to be analyzed and each bar 78 corresponds to an index-point position in such column with which it is adapted to cooperate. The rotation of the brushes 71' is so timed that the bars corresponding to a given index-point position are in contact with brushes 71' at the instant the brushes 42 are reading the same index-point positions on the card.

The commutator block 73 cooperating with the brush 72' is adapted to shunt the sorting magnet 56 during special sorting operations. In order to permit normal sorting operations there is provided a switch 111 which may be opened to prevent shunting of the sorting magnet. This switch may be mounted in the casing 66 or exterior thereto and may be of any desired type. The block 73 as above mentioned, is provided with a single contact 79 which extends along the greater part of the periphery of the cut-out portion of the block and cooperates with the brush 72' in a manner and for a purpose explained more in detail hereinafter.

The construction of a single control block will now be described, and since they are all alike, the description of one is sufficient to understand all of them constituting the battery as shown in Fig. 4. The control block is shown particularly in Figs. 6, 7, 8, 9, 10, 11, and 12.

Preferably the control block is formed of three separate pieces 85, 86, and 87 of bakelite or other insulating material. The piece 85 is of U-shape or channel shape and the sides are correspondingly stepped so as to form three different levels 88, 89, and 90, shown particularly in Fig. 6. Secured to one of the arms of U-shaped element 85 and complementally stepped is piece 86, while upon the other arm also complementally stepped is element 87. The elements 85, 86, and 87 are secured together by screws 91 or any other desired securing means. Upon the top of element 87 is secured scale 92 for the setting count.

The elements 86 and 87 are provided with inwardly directed shoulders 93 which cooperate with the shoulders 94 provided upon the selector slide 95 of insulating material. Fixed to one side of the slide 95 is pointer 96 cooperating with scale 92. The slide 95 is of unique form as shown particularly in Figs. 10 and 11 for a purpose hereinafter described and is provided with three distinct levels, *a*, *b*, and *c*. Each slide is provided with a handle portion 97 which may be of any desired configuration.

Each arm of U-shaped element 85 is provided with a series of slots 98 of three different lengths corresponding to the stepped portions therein, and in each slot there is disposed a guide rod 99 having a head 100 in contact with a transversely disposed rod 101 preferably of circular cross section.

The supporting rods 99 are of sufficient length so that the lower ends thereof extend into the bores 102 provided in the member 85 from the bottom of the slot 98 to the bottom of the member 85 whereby said rods are guided in their reciprocating movement. Surrounding the rods 99 and abutting against the heads 100 and the

bottom of the slots 98 so as to urge the rods 99 upwardly and thereby the transverse rods 101, are the coil springs 103.

Due to the construction just described the rods 101 which are of conducting material are maintained at each end in contact with the contacts 104 which are mounted upon elements 86 and 87 adjacent each of the slots 98. The contacts 104 are preferably of right angular construction as shown with portions extending inwardly into the slots 98. The contacts 104 are all insulated from one another and are secured to the elements 86 and 87 and also to the leads 105 by screws 106.

Located between the legs of the U-shaped element 85 and extending beneath all of the rods 101 are a series of three bars 107, 108, and 109 of insulating material and shaped as shown in Figure 12 so as to accommodate the bars to the stepped levels 88, 89, and 90. The bars are of a width so as to substantially fill the space between the legs of the member 85 thereby utilizing the interior sides of said legs as guides and the bars 107, 108, and 109 are urged upwardly into contact with the rods 101 by the coil springs 110 abutting the member 85.

As will be noted from Fig. 12, the bars end close to one another at their ends and the springs 110 are located at the non-stepped portions preferably two to each bar.

Each bar is provided with a recess 112 extending substantially the non-stepped length and along a side of the bar. In recess 112 of bar 107 are wiper contacts 114 which are electrically connected by the metal strip 115 while in the recesses 112 of bars 108 and 109 are similar wiper contacts 116 and 117 respectively, and similar connecting strips 118 and 119 respectively.

The wiper contacts 114, 116, and 117 cooperate with contacts 120 secured to member 85 by screws 121 adjacent openings 122 provided in member 85 leading to the longitudinally extending groove 123, through which openings and groove the leads to the contacts 120 may be conveniently carried.

The scale 92 as shown particularly in Fig. 7, is divided into twenty-six indices which correspond with the twenty-six tabulated positions upon a record card. They are numbered from 1 to 26. In addition to these there is provided the "all out" position and this position is also furnished with the slots 98 in the member 85 and the supporting rods 99 and transverse rod 101 cooperating with contacts 104. Each position from 1 to 26 upon the scale 92 is positioned adjacent a rod 101 which corresponds with that position and the contacts 104 for each rod and the rod 101 therefore are connected in series with the commutator bars of the first and second commutator blocks. The third and fourth commutator blocks would have their bars connected in like manner to the second control block rods 101.

When using the group selector the commutator bars 78 corresponding to the index-point position 12 are not used in the circuits, as will be noted upon reference to Fig. 16. These bars are not needed since according to the code used, set forth below, sufficient combinations can be built up from those used to take care of all twenty-six tabulated positions as well as the "all out" position.

The bars 107, 108, 109 are positioned and extend in a certain particular manner with respect to the rods 101 in the member 85. Bar 107 extends

from the "1" position to and including the "9" position. Bar 109 extends from and including the "10" position to and including the "19" position. Bar 108 extends from and including the "20" 5 position to and including the "26" position.

Bar 107 has the strip 115 and the contacts 114 thereon connected in series with the "0" position or bar of the first commutator block, and bar 108 has the strip 118 and the contacts 116 thereon 10 connected in series with the "11" position or bar of the first commutator block. Bar 109 has its strip 119 and contacts 117 connected in series with "11" position or bar of the second commutator.

15 The detail construction of the special group selector mechanism and its connections with the sorting machine having been described, the operation of the device in selecting certain cards will now be described. The selector device depends 20 for its operation upon the fact that an unperforated card passing the analyzing brush will not affect the sorting magnet. Not having a perforation in any index point position, the unperforated card will pass beneath the blade ends 54 of all of 25 the guide blades leading to sorting pockets and will be guided eventually into the "R" or "reject" pocket which usually is the first pocket to the left of the analyzing brush as viewed in Fig. 1. It will be perceived that if it is desired to separate 30 certain specified cards from the others it is merely necessary to nullify the presence of the identifying perforations in the cards to be selected in order to permit said cards to be conveyed to the "R" pocket while the operation of the sorting 35 magnet for the undesired cards will not be interfered with. In other words, the present invention contemplates selection by rejecting the desired cards and diversion of the undesired cards so that the former will be guided to the "R" pocket and 40 the latter to some other pocket such as, in the present case, the "12" pocket.

The group selector device is so arranged that the effect of each of the perforations representing the identifying number and those adjacent thereto upon each side of the identifying number in the desired cards are neutralized by setting the selector slide with the pointer 96 adjacent the identifying number upon scale 92 so that an open circuit will occur when each of said perforations 45 is sensed by an analyzing brush 42 while the perforations in undesired cards will affect the brush relay so as to set up a circuit which eventually will be effective to control the sorting magnet at the "12" position to divert the undesired card to the "12" pocket.

In order to accomplish the foregoing result the selector slides are set so that no circuit can be established therethrough in any of the index-point positions and those positions adjacent the 50 index-point positions representing the group number of the cards to be selected while the sorting magnet is shunted except at the "12" position and during the gap between successive cards. For this reason the gap 124 between the ends of 55 the contact 19, see Fig. 13, is of a length to permit the establishment of the shunt circuit for the sorting magnet from the "9" to the "11" position, the shunt being removed at the "12" position of one card and reestablished slightly before the "9" 60 position of the card immediately following.

In order to understand how the rods 101 when operated upon by the selector slide select the required cards, it is necessary to set forth the special code used in the punching of the data upon the 65 record cards.

The usual code for punching data upon the record cards is as follows: There are a series of columns upon the record cards having the characters from "0" to "9", "11" and "12" thereon. Two columns are utilized to form the tabulated 5 position as follows:—1="01"; 2="02"; 3="03"; 4="04"; 5="05"; 6="06"; 7="07"; 8="08"; 9="09"; 10="10"; 11="11"; 12="12"; 13="13"; 14="14"; 15="15"; 16="16"; 17="17"; 18="18"; 19="19"; 20="20"; 21="21"; 22="22"; 10 23="23"; 24="24"; 25="25"; 26="26".

This usual code is unsuitable for the group selection used in the present invention for the following reasons. If the usual code were followed in punching the tabulated position "9" and it was 15 desired to secure two index point positions upon each side of "9" then in such case the selector switches would be set for "07", "08", "09", "10", and "11".

From these settings it will be noted that in the 20 first column there will be "0" and "1" set while in the second column there will be "7", "8", "9", "0", and "1" set. Such a setting will cause the following tabulated positions to fall into the "R" or "reject" pocket, viz. 1, 7, 8, 9, 10, 11, 17, 18, 19, 25 and 0. Ten tabulated positions would fall while only five were wanted.

It is for this reason that this code is impractical as far as group selection is concerned and the special code described below must be used in 30 order to get exactly the classifications for which the selector slides are set. In this code the character "11" is shown as "X" and the character "12" as the "?" or "unknown" value.

In the special code 1=01; 2=02; 3=03; 4=04; 35 5=05; 6=06; 7=07; 8=08; 9=09; 10=0X; 11=1X; 12=2X; 13=3X; 14=4X; 15=5X; 16=6X; 17=7X; 18=8X; 19=9X; 20=X0; 21=X1; 22=X2; 23=X3; 24=X4; 25=X5; 26=X6. The unknown value is 12 and 11. If 40 more than 26 tabulated positions are utilized, then the code is enlarged in the same manner since this number of tabulated positions is taken merely because this is the number used in finger print records. The code and group selector of 45 the present invention can obviously be adapted to other fields.

The new code described above for punching the data upon the record cards will operate as follows, and in order to fully illustrate the distinction over the usual code first described, the same tabulated position "9" will be chosen. When the slide in the control block is set with the pointer 96 at the "9" position on scale 92, then the following settings are made, viz., "07", "08", "09", 55 "0X" and "1X".

In this case from these settings the following counts would fall into the R pocket, viz., 7, 8, 9, 10 and 11 which are coded on the card as set forth above, viz., "07", "08", "09", "0X" and "1X". 60 As will be noted, the setting also includes the following three settings—17, 18 and 19, but it will be understood from the new code set forth above that there are no such combinations therein and therefore these tabulated positions are not selected.

The operation of the selector slide shown in Figs. 10 and 11 with relation to the control block will now be described. When the selector slide is placed with the pointer 96 at the "1" position 70 of the scale 92 shown particularly in Fig. 7, then the level "a" thereof will contact rods 101 at positions 1, 2, and 3 and depress the same so as to break the circuit between the rods depressed and their respective contacts 104. The rods 101 75

at positions 1, 2, and 3 when depressed will de-press bar 107 directly thereunder and cause a break between contacts 114 carried by bar 107 and contacts 120. These circuit breaks correspond to code positions "01", "02", and "03" and will therefore deenergize brushes 42 when analyzing these positions and thereby cause a record card having these positions punched to fall into the "reject" pocket, or in other words, be selected.

When the selector slide is placed with its pointer at the "2" position on the scale then rods 101 at positions "1", "2", "3", and "4" will be depressed. When placed at "3" position then rods 101 at positions "1", "2", "3", "4", and "5" will be depressed. The chart below gives at the left of the equation the position at which the slide is placed and at the right the positions of the rods 101 depressed or which have their circuits broken.

1	=1, 2 and 3
2	=1, 2, 3 and 4
3	=1, 2, 3, 4 and 5
4	=2, 3, 4, 5 and 6
5	=3, 4, 5, 6 and 7
6	=4, 5, 6, 7 and 8
7	=5, 6, 7, 8 and 9
8	=6, 7, 8, 9 and 10
9	=7, 8, 9, 10 and 11
10	=8, 9, 10, 11 and 12
11	=9, 10, 11, 12 and 13
12	=10, 11, 12, 13 and 14
13	=11, 12, 13, 14 and 15
14	=12, 13, 14, 15 and 16
15	=13, 14, 15, 16 and 17
16	=14, 15, 16, 17, 18 and 19
17	=14, 15, 16, 17, 18, 19 and 20
18	=15, 16, 17, 18, 19, 20 and 21
19	=16, 17, 18, 19, 20, 21 and 22
20	=17, 18, 19, 20, 21, 22 and 23
21	=18, 19, 20, 21, 22, 23 and 24
22	=19, 20, 21, 22, 23, 24 and 25
23	=20, 21, 22, 23, 24, 25 and 26
24	=21, 22, 23, 24, 25 and 26
25	=22, 23, 24, 25 and 26
26	=23, 24, 25 and 26

From the above chart it is seen that for positions 3 to 15 two rods 101 upon each side of the particular position are depressed, that for 16 two below and three above are depressed and that for 17 to 23 three positions upon each side are depressed. This is caused by the particular spacing of the rods 101 in the control block and also by the stepping of the rods 101 and the levels a, b, and c of the slide itself.

The bottom level a of the slide is wide enough to depress five rods 101 at the left of the control block as shown in Fig. 6 upon the level 88. When the level 89 is encountered by the slide then the level b of the slide comes into action with the level a and levels a plus b is wide enough to depress six rods 101. However, as will be noted upon Fig. 6 the rods 101 at the beginning of level 89 are somewhat further spaced apart and this results in the slide only depressing five rods up to the 15 position even though levels a and b are in action. However at the 16 position level c also comes into action which when added to levels a and b renders the slide capable of depressing seven rods 101. However, due to the spacing of the rods 101 at the 16 position only six positions are depressed but thereafter beginning with 17 position three positions upon each side are depressed.

For the purpose of preventing excessive spark-

ing at the brush 72' when the circuit is broken at the "12" position, there is provided a condenser 113 connected in parallel with the sorting magnet and contained within the casing 66 and a glass insert 114' which is set flush with the contact 79 where the brush 72' breaks the circuit through contact 79. The glass insert prevents the spark created by the break in the circuit from burning the insulating material of which block 73 is constructed.

The circuits from the analyzing brushes 42 through the commutators and the selector block will now be briefly traced to the sorting connection 39. Reference is made to Fig. 16 wherein the brushes 42 have opposite them the number of the column upon the record card which they analyze. Brush 42 at the first column is connected in series with the brush 71' of first commutator 76, while brush 42 for the 2 column is connected in series with the brush 71' of the second commutator and so forth. In Fig. 16 only the circuits for the first and second commutators and the control block for these two commutators is shown. The other eighteen commutators and nine control blocks are similarly connected with the brushes 42 and the sorting connection 39. In finger print sorting the brushes 42 for "1" and "2" columns together with the first and second commutators and control block associated therewith will analyze the data upon the record card relating to one finger. The other eighteen brushes 42 with associated commutators and control blocks will take care of the data relative to the other nine fingers.

From brush 42 at the first column or "1" position the circuit goes by wire 125 to brush 71' of the first commutator and from brush 42 at "2" position a wire 126 leads the circuit to brush 71' of the second commutator by means of lead 82. From commutator bar 78 at "1" position on the second commutator a circuit 127 leads to one of the contacts 104 with which rod 101 at "1" position contacts. A circuit 128 leads from the other contact 104 of rod 101 at "1" position to rod 101 at "21" position and then by circuit 129 to rod 101 at "All out" position and from there by lead 130 to the sorting connection 39.

From bar at "2" position on second commutator a lead 131 leads to rod 101 at "2" position, then by lead 132 to rod at "22" position, and then by lead 129, rod at "All out" position and lead 130 to 39.

From bar at "3" position on second commutator a lead 133 to rod at "3" position, then lead 134 to rod "23" then in same manner as above to sorting block through lead 129.

From bar at "4" position on second commutator a lead 135 goes to "4" position in block and then lead 136 to "24" and thence 129 to 39. From bar at "5" position circuit goes by lead 137 to rod 60 at "5" position and then lead 138 to rod at "25" position and then by lead 129 to 39. From bar at "6" position circuit goes by lead 139 to rod at "6" position in block and then by lead 140 to rod at "26" position and then by lead 129 to 39.

From bar at "7" position the circuit is somewhat different and goes by lead 141 to rod at "7" position. Thence by lead 142 to lead 143, lead 144 to lead 129 and thence to sorting connection.

From bar at "8" position a lead 145 goes to rod 70 "8" in block and thence by lead 142 to 39. Also from bar "9" a lead 146 goes to rod "9" and thence by 142 to 39.

With respect to the first commutator it will be seen in Fig. 16 that similarly the commutator

bars "1", "2", "3", "4", "5", "6", "7", "8", and "9" are connected to rods at positions "11", "12", "13", "14", "15", "16", "17", "18", and "19" respectively in the selector block and the respective circuits go by leads 142, 143, 144, 129, "All out" rod and lead 130 to sorting connection 39.

The "0" bar of the second commutator is connected by lead 147 with the rod at "20" position in the block and thence by leads 143, 144, 129, 10 and 130 to 39.

The "11" or "X" position of the second commutator is connected by lead 148 to bar 109 and thence by lead 149 to 144 and thence to 39.

The "0" position of the first commutator is connected by lead 150 with bar 107 and thence by lead 151 to rod at "10" position and thence by lead 142 to 39.

The "11" or "X" position of the first commutator is connected by lead 152 to bar 108 and 20 thence by leads 149, 144, etc. to 39.

The "12" or "?" positions in the commutators are unconnected or "dead".

To illustrate the manner in which the slide 95 controls the above circuits, several specific examples are given. As set forth above when a circuit is broken then a card is selected for the "reject" pocket.

We will assume that the slide is placed at the "1" position in the selector block. Then as described above, positions "2" and "3" will also be depressed and a break is made in the circuits 127, 131, and 133. In addition, when the slide is placed at "1" position the bar 107 or the "0" bar is also depressed thereby breaking circuit 150 leading to the "0" position in the first commutator.

The circuits 127, 131, and 133 go to the "1", "2" and "3" positions in the second commutators. The 1, 2, and 3 tabulated positions however, when coded in the manner set forth above will appear 40 in the first two columns of the card as "01", "02" and "03". In order to select cards having these values, the "0" circuit in the first column cooperating with the first commutator must be broken and the "1", "2", and "3" circuits in the second column cooperating with the second commutator must be broken and this is what takes place when the slide is set at position "1". Such a setting therefore immediately selects not only tabulated position 1 but also 2 and 3.

If we assume that the slide is placed with its pointer 96 at tabulated position 15 then according to the chart above tabulated positions 13, 14, 16, and 17 will also be depressed. These positions as will be noted from the special code above correspond to "3X", "4X", "5X", "6X", and "7X". As pointed out above "X" is the "11" position on the commutators. Therefore, to make a proper selection the circuits leading to the positions "3", "4", "5", "6", and "7" in the first column must be 55 broken and in the second column the circuit going to the "X" or "11" position.

From Fig. 16, when the rods at "13", "14", "15", "16" and "17" positions are depressed, then the circuits going to positions "3", "4", "5", "6", and 65 "7" of the first commutator are broken. However, when the slide is placed at position 15 then the bar 109 is also depressed breaking circuit 148 going to "11" position in the second commutator.

If we place the slide at "8" then 6, 7, 8, 9 and 70 10 positions are depressed. The code values are "06", "07", "08", "09", and "0X". In the first commutator "0" should be "dead" and in the second "6", "7", "8", "9" and "X".

From Fig. 16 when rods 101 at 6, 7, 8, and 9 75 are depressed then the circuits 139, 141, 145, and

146 are broken leading to positions "6", "7", "8" and "9" of the second commutator. When rod 101 at 8 is depressed then the circuit going through bar 107 through lead 150 to "0" position in first commutator is broken.

However, when the slide is at 8 the bars 107 and 109 are both depressed. Bar 107 breaks lead 150 already broken while bar 109 breaks the circuit to "11" or "X" position in the second commutator through lead 148. Therefore the required circuits are broken and the required cards are selected.

It is believed that the operation of the selector slides is clear from the above.

It is of course desirable that the various contacts and leads be easily accessible and also that normally they be fully protected. In order to accomplish these objects a metal plate may be provided bridging the gap between each selector block. This metal plate may be secured to the blocks by screws or the like or secured to the casing itself.

It will be assumed that it is desired to select a given group of cards corresponding to the "count" given to each of the ten fingers. In such case as set forth above in order to eliminate errors in the "count" due to the human element the numbers on each side of the given "count" are automatically selected by the slides.

If the given "count" for each of the ten fingers is 5, 4, 12, 17, 18, 11, 2, 10, 9, and 8 then in addition to this "count" there will be chosen all combinations that will fall within:

3	2	10	14	15	9	1	8	7	6	35
4	3	11	15	16	10	2	9	8	7	
5	4	12	16	17	11	3	10	9	8	
6	5	13	17	18	12	4	11	10	9	
7	6	14	18	19	13		12	11	10	
			19	20						40
			20	21						

This is accomplished by merely setting each slide at the given "count" and then the requisite "dead" bars are set up in each of the twenty commutators to take care of the code values punched in the cards corresponding with the "count".

The switch 111 is closed and the ordinary brush holder carrying the brush 53 is removed and the brush holder 32 put in its place. If needed the carriage 31 may be shifted in well known manner to align the twenty brushes 42 with the twenty columns upon the record card. The selector slides are then set as above described and the machine is now ready to carry out the sorting operation after the cards have been placed in the magazine.

For the reasons above given any number falling within the combination of "counts" above will be non-conducting and a flow of current cannot be established through the commutator bars representing any number within the combination or grouped classification when the brushes 42 encounter the perforations representing such number and any card having a number within the grouped classification will not effect the circuits in any way since the only way in which the brush relay 57 can be energized is through a perforation in the card analyzed, a brush 42, circuit 50, brush 71' and a commutator bar 78 and associated circuit through a rod 101 to the sorting connection 39 and lead 58.

When a card is analyzed having a perforation outside of the combination group above specified a circuit will be established as follows: Source 12, line 13, contact 79, brush 72', switch 111, previously closed, brush relay 57, thereby closing 75

contacts 51a, line 58, sorting connection 39, line 130, then through the rods 101 or bars 107, 108, and 109 to the commutator bars 78, then brush 71', line 50, brush 62, contact roll 45, contact roll 5 brush 59, line 160, brush 60, commutator 64, common brush 61 and line 17 back to source.

The closing of contacts 51a by relay 57 sets up a holding circuit for the relay through brush 63, segment 62, common brush 61 and line 17, 10 to the source 12. However, the sorting magnet 56 is shunted by contact 79 of block 73 so that for the time being, nothing else happens. When the card under the brushes 42 reaches the "12" 15 position the gap 124 breaks the shunt circuit and transfers the holding circuit of relay 57 to the sorting magnet 56 thereby energizing said magnet and causing the card to go to the "12" pocket.

It may happen that none of the perforations 20 in a card analyzed by the brushes 42 corresponds to the perforations representing a number within the group classification of the desired cards. When such is the case the first perforation encountered by one of the brushes 42 will set up the 25 relay 57 and the perforations subsequently encountered will have no effect although circuits through rods 101 will be set up.

This invention has been so devised as to form a compact and self contained device which may be 30 readily mounted upon an existing sorting machine without requiring any changes other than a slight reconnection and rearrangement of the circuits and the attachment of suitable supporting brackets to the frame of the machine. It may be readily connected and disconnected at the will 35 of the operator and imposes no appreciable additional load on the driving motor.

The present invention is shown as used to select record cards with twenty columns. However, as is obvious this number may be either increased 40 or diminished.

Nor is the invention limited to use in connection with a sorting machine alone, since it may be built in the form of an attachment to a tabulating machine to select the card to be operated 45 upon by said machine. This may be readily accomplished by delivering the desired cards directly to either the card magazine or the feeding rollers of the tabulating machine instead of accumulating the cards in the "reject" sorting 50 pocket.

I claim:—

1. In a record controlled machine, a machine control element, a circuit therefor; a pair of commutators associated with said circuit, each 55 commutator associated with one of a pair of columns in the controlling records in which pair of columns a classification number comprising one or more digits is recorded; and a unitary control device cooperating with said circuit and said commutators and including a single setting member 60 settable in accordance with a predetermined classification number which may comprise one or more digits and controlling said device to cause the control element to be operated in accordance 65 with both the records having the predetermined classification number and a predetermined number of other classifications according to a predetermined system.

2. In a machine controlled by records identified 70 by classification numbers which may consist of several digits recorded in the index-point positions of a field comprising several columns, a machine control element, a circuit for controlling said element, a plurality of series of contact elements each corresponding to an index point in

one of the columns of a field, and a unitary control device cooperating with said circuit and said contact elements and including a single setting number positionable to a predetermined classification number and controlling said device 5 whereby the control circuit is identically controlled in accordance with the predetermined classification number and a plurality of others according to a pre-arranged system.

3. In a machine controlled by records identified 10 by classification numbers recorded in the index-point positions of a field comprising several columns each of which classification numbers may include several digits, a machine control element, a control circuit therefor, a plurality of contact 15 elements each associated with an index-point position in one of said columns of a field, a series of switching devices connecting said contact elements to said circuit, and a single member settable in accordance with a predetermined classification 20 number and operating the switching devices in combinations according to a predetermined plan whereby the control element is controlled in accordance with both records having the predetermined classification and records having 25 a plurality of other classifications according to the predetermined plan.

4. In a machine controlled by records identified 30 by classification numbers recorded in the index-point positions of a field comprising several 35 columns which classification numbers may include several digits, a machine control element, a control circuit therefor, a plurality of contact elements each associated with an index-point position; a series of switching elements connecting 40 said contact elements to said circuit, some of said switching elements corresponding to classification numbers; and a single member settable in accordance with a predetermined classification number and operating the switching elements in 45 combinations according to a predetermined plan whereby the control element is controlled in accordance with both records having the predetermined classification and records having a plurality of others according to the predetermined plan.

5. In a machine controlled by records identified 50 by classification numbers which may comprise several digits recorded in a field including several columns of each record, sorting mechanism, a circuit for controlling the operation of said mechanism, contact elements each corresponding to one of the index-point positions of one of the columns in which the classification number is recorded, a series of switching devices connecting 55 said elements with said circuit, and a manually settable member adapted to operate said switching devices in groups in which the number of switches operated varies according to the setting of said number, said switching devices when operated controlling the circuit to segregate both the records bearing a predetermined classification number and the records having a predetermined number of other classification numbers from the other records of a batch.

6. In a device of the character described, sorting 65 mechanism, a plurality of circuits for controlling said sorting mechanism, a plurality of commutator devices, a plurality of commutator bars in each commutator device, one for each circuit, a control block for each pair of commutator devices, a plurality of spaced contacts in said control block connected to each circuit of the commutator bars of the associated commutator devices, a plurality of contact rods resiliently urged against said contacts and means co- 70 75

operating with said control block to move a group comprising a variable number of rods away from said contacts.

7. In a device of the character described, sorting mechanism, a plurality of circuits for controlling said sorting mechanism, a plurality of commutator devices, a plurality of commutator bars in each commutator device, one for each circuit, a control block for each pair of commutator devices, a plurality of spaced contacts in said control block connected to each circuit of the commutator bars of the associated commutator devices, a plurality of contact rods resiliently urged against said contacts and a selector slide cooperating with said control block to move a group comprising a variable number of rods away from said contacts.

8. In a device of the character described, sorting mechanism, a plurality of circuits for controlling said sorting mechanism, a plurality of commutator devices, a plurality of commutator bars in each commutator device, one for each circuit, a control block for each pair of commutator devices, a plurality of spaced contacts in said control block connected to each circuit of the commutator bars of the associated commutator devices, a plurality of contact rods resiliently urged against said contacts, means cooperating with said control block to move a group comprising a variable number of rods away from said contacts and circuit breaking means for certain of said circuits located in association with said contact rods.

9. In a device of the character described, sorting mechanism, a plurality of circuits for controlling said sorting mechanism, a plurality of commutator devices, a plurality of commutator bars in each commutator device, one for each circuit, a control block for each pair of commutator devices, a plurality of spaced contacts in said control block connected to each circuit of the commutator bars of the associated commutator devices, a plurality of contact rods resiliently urged against said contacts, means cooperating with said control block to move certain rods away from said contacts, bars extending transversely of said contact rods having circuit breaking means for certain of said circuits associated therewith and said bars being operated conjointly with said rods by said control block cooperating means to effect a selective sorting of a plurality of classifications.

10. A control block for a sorting mechanism having a plurality of circuits comprising a member having a channel extending longitudinally thereof and a series of transverse aligned slots in each of the opposed walls of the channel, contacts located in said slots, transverse contact rods slidably mounted in said slots so as to span the channel and normally held in contact with said contacts and means for selectively moving said rods away from said contacts in group, comprising a variable number of rods to secure a predetermined sorting of a plurality of classifications by said sorting mechanism.

11. In a device of the character described, in combination with means to sort records having designations thereon, settable means adapted to be positioned to designate the selection of a designation of certain value, a plurality of control means, selecting means controlled by the settable means to select a predetermined number of the control means upon a single positioning of the settable means, means associated with the said selecting means whereby the number of control

means selected by the said positioning of the settable means increases with the higher value of the designation selected by the settable means and means controlled by the selected control means to render the sorting means effective to sort the records having the selected designation and in addition thereto those records having other designations bearing a predetermined relationship to the selected designation, the predetermined relationship of the designations varying in accordance with the value of the designation selected.

12. In a record controlled machine, an element for controlling machine operation, a plurality of record sensing means, each for sensing one column of a field in the controlling records comprising a plurality of columns in which field classification numbers comprising one or more digits are recorded by means of designations disposed in said columns, a group of devices connected to the record sensing means for operating the machine controlling element; and means to control the effect of the group of devices on the machine controlling element including a series of finger pieces each common to a plurality of said columns and selectively settable to correspond to any classification number appearing in said columns, said finger pieces controlling the group of devices to cause the machine controlling element to effect a given machine operation with respect to records having the selected classification numbers and records having at least one other predetermined classification number in said columns and to effect a different machine operation with respect to records lacking either the selected classification or the predetermined classification.

13. In a sorting machine for perforated records identified by classification numbers each number being recorded by means of designations placed in a field comprising several columns of a record; a series of record sensing devices, each associated with a column of a record; sorting mechanism, means to control the sorting mechanism; a series of control devices for the sorting control means, each control device being associated with one of the devices sensing a column of a record; and selector means for said series of devices for controlling the effect of said series of devices on the sorting control means, said selector means including a series of setting members, each controlling at least two of said devices and manually selectively settable to correspond to any classification number appearing in the columns with which the control devices are associated and when so set causing the selector means to control the sorting control means whereby to segregate not only the records having the selected classifications but records having at least one other classification.

14. In a record controlled machine, means to sense data designations in a field comprising a plurality of columns in which columns of classification numbers which may consist of one or more digits are recorded by means of designations disposed in said columns, machine control means for controlling the operation of the machine, a plurality of rotary switching elements each connected to the sensing means so as to be associated with one column of the field in which the classification designations appear, selector means for connecting the rotary switching elements to the machine controlling means, said selector means including a series of switch members each common to a plurality of the rotary switching

- elements, each of said switch members being manually selectively settable to correspond to any classification number appearing in the columns with which the rotary switching elements controlled by said member are associated, each switch member when set to correspond to any selected classification number causing the rotary switch elements to operate the machine control means in accordance with not only said selected classification number but at least one other classification number in said columns.
15. In a record controlled machine, a plurality of electric record sensing devices each associated with a column of a field in which classification numbers comprising one or more digits are recorded by means of designations disposed in said columns, rotary switch means having a plurality of contact wiping elements each connected to one of the sensing devices, contact means associated 20 with the wiping elements, said wiping elements being operative to close circuits from the sensing devices through the contact means in a predetermined order according to the disposition of the designations in the columns of the records, machine operation control means including a magnet in circuit with the sensing devices and contact wiping elements, and a plurality of manual members for controlling the circuits through the wiping elements and contact elements, each manual member operating the contact means to control the circuits through a plurality of the wiping elements and manually selectively settable to correspond to any classification number appearing in the columns associated with said plurality of wiping elements and when so set causing the magnet to be controlled in accordance with not only the selected classification number but also in accordance with at least one other classification number.
- 40 16. In a machine controlled by records identified by means of groups of classification numbers each recorded by means of designations placed in the columns of a plurality of classification fields each of which fields consists of at least two columns, means for sensing all the columns, sorting mechanism, means to control the operation of the sorting mechanism; and a selector device for rendering the sorting control means responsive to designations in the records, including a series of 45 manually settable members, one for each classification field, said members being each manually selectively settable to correspond with any classification number in the columns of the field with which said member is associated, and means controlled by each member for causing the sorting control means to control the sorting mechanism in accordance with not only the selected classification number appearing in the associated field but also in accordance with at least one other classification number in said field.
17. In a machine controlled by records having a classification number field consisting of a plurality of columns in which classification numbers comprising one or more digits are recorded 65 by means of designations disposed in said columns, a plurality of record sensing devices, each for sensing one column of said field; a manual selector device common to a plurality of the sensing means and manually selectively settable to correspond to any classification number appearing in the columns sensed by the associated sensing means, a machine controlling element, and operating means jointly controlled by the selector device and sensing means for operating the 70 machine control element, said operating means 75

being rendered operative by the selector device, when the latter is set to correspond with a selected classification number appearing in said field, to control the machine control element in accordance with not only the selected classification but another classification number in said field.

18. In a record controlled machine, electric means to sense classification data designations in a field comprising at least two columns, a machine operation controlling element; rotary switching devices, each corresponding to one of said columns and connected to the analyzing means; and a manual switching device connecting the rotary switching devices to the machine controlling element and including a single selectively settable manual member for controlling the effect of a plurality of the rotary switching devices on the machine controlling element, said manual member when selectively set in accordance with a given classification number setting the manual switching device to cause rotary switching devices to operate the machine controlling element in accordance with not only the given classification number but also a predetermined number of other classification numbers.

19. In a record controlled machine, an element for controlling machine operations, a plurality of record sensing devices each for exploring one column of a field in which classification data is recorded in the controlling records, a group of devices connected to the record sensing devices for operating the machine controlling element; and means to control the effect of the group of devices on the machine controlling element including a member common to at least two of the sensing devices and the devices of said group associated therewith, said member being selectively settable to correspond to any single classification number within said columns and controlling the control means to cause the group of devices to operate the machine control element in accordance with said selected classification number and at least one other classification number.

20. In a sorting machine, electric means to sense classification data designations in a field comprising at least two columns, sorting mechanism with means to control the operation of the sorting mechanism, a group of rotary switches, each switch corresponding to one of said columns and connected with the analyzing means, and a manually operable switching device connecting all the rotary switches with the control means for the sorting mechanism, said switching device having a manually selectively settable member for controlling the effect of data designations in said field on the control means for the sorting mechanism through said group of rotary switches, said manual switching device controlling the group of rotary switches to cause the sorting mechanism control means to be operated in accordance with both a predetermined classification number in said field and a predetermined number of others.

21. A selector for record controlled machines comprising a plurality of rotary contact devices one for each column of a field in which classification numbers are recorded in the controlling records; and a switching device common to said plurality of contact devices, said switching device including a scale of classifications, a longitudinally movable switch bar selectively settable in accordance with one of the classifications on said scale, means operated by the switch bar for controlling the number of effective contacts made

by said plurality of contact devices, and manual means for selectively setting the switch bar in accordance with the scale of classifications.

22. In a sorting machine, sorting mechanism including sorting control means to control the distribution of records by the sorting mechanism; a plurality of record sensing devices, each device for exploring a column of a field in the controlling records comprising a plurality of 5 columns in which field classification numbers which may consist of one or more digits are recorded; a group of devices connected to the sensing devices for operating the sorting control means in accordance with the classification number 10 designations in said record field, and classification control means to control the effect of said group of devices on the sorting control means including a member common to at least two columns of the field, said member being 15 manually selectively settable to correspond to any classification number within said columns and when set conditioning the classification control means to control the sorting control means through said group of devices in accordance 20 with both the selected classification and at least one other predetermined classification whereby records bearing either the selected or the predetermined classifications will be segregated 25 from records not bearing either the selected or the predetermined classifications.

23. In a machine controlled by records identified by a plurality of classification numbers which may consist of more than one digit each number being represented by designations in a classification field comprising a plurality of columns, 5 machine operation controlling means, means to sense the designations in said field, means co-operating with the sensing means for operating the machine operation controlling means in accordance with all the classification designations, 10 and a series of variably settable members for controlling the effect of the operating means on the operation controlling means, each member being common to at least two of the columns of said field and settable to correspond to a pre-determined single classification number appearing 15 in said fields and adapted to set the operating means to cause the machine operation controlling means to be operated in accordance with not only the predetermined classification number but also in accordance with a group of classification numbers in said field in which each classification bears a predetermined relation to the predetermined classification, all of said members conjointly controlling the operating 20 means whereby the machine operation controlling means is operated in accordance with a plurality of groups of classifications.
